(57) CLAIM

The ornamental design for a bottle, as shown and described.

DESCRIPTION

FIG. 1 is a front side and top perspective view of a bottle of the present design.

FIG. 2 is a rear side and top perspective view of a bottle of the present design.

FIG. 3 is a front side elevation view of the bottle of the present design.

FIG. 4 is a rear side elevation view, opposite of the view in FIG. 3, of the bottle of the present design.

FIG. 5 is a left side elevation view of the bottle of the present design.

FIG. 6 is a right side elevation view, opposite of the view in FIG. 5, of the bottle of the present design.

FIG. 7 is a bottom plan view of the bottle of the present design; and,

FIG. 8 is a top plan view of the bottle of the present design. The broken lines illustrated in FIGS. 1 and 3 show a cap on the top of the bottle, which forms no part of the claimed design.

1 Claim, 7 Drawing Sheets
